FRITZ ROSSBACH-ROUSSET, OF TEMPELHOF, GERMANY, ASSIGNOR
TO THE FIRM G. GOLIASCH & CIE., METALLWAARENFABRIK, OF
BERLIN, GERMANY.

DEVICE FOR IGNITING AND CUTTING OFF GAS-JETS.

SPECIFICATION forming part of Letters Patent No. 767,663, dated August 16, 1904.

Application filed December 12, 1901. Serial No. 85,713. (No model.)

To all whom it may concern:

Be it known that I, FRITZ ROSSBACH-ROUSSET, a subject of the King of Prussia, German Emperor, residing at Tempelhof, near Berlin, in the Kingdom of Prussia, German Empire, have invented a new and useful Device for Igniting and Cutting Off Gas-Jets, of which the following is a specification.

This invention has relation to appliances for lighting and extinguishing gas-jets by variations of the pressure of the gas.

In the automatic gas lighting and extinguishing systems hitherto proposed the operations of lighting and extinguishing has been dependent upon maintained pressure variations—that is to say, if the lights are to be extinguished by a reduction of the pressure in the supply-mains below the normal pressure this pressure has to be maintained so long as the lights remain extinguished, the lighting being then effected by an increase of the pressure above the normal and its subsequent reduction to normal pressure, which of course has to be maintained until the lights are again extinguished. Such a system could not be made use of in cities unless the lamps to be lighted and extinguished at given periods were included in a distribution entirely independent of or separate from the system of distribution in which are included all the lamps or lights that are not to be arbitrarily lighted and extinguished—as, for instance, house-lights in contradistinction to street-lights, as it is not possible or desirable to supply gas for house illuminating or heating purposes for a definite period and then cut off the supply for a definite period for obvious reasons.

My invention has for its object the provision of means whereby pressure variations may be temporarily or momentarily produced in a supply pipe or main or in a system of gas distribution independently of the normal pressure in such pipe, main, or system of distribution whereby any well-known appliances capable of controlling the lighting and extinguishing of a jet or any number of jets are set in operation.

My invention has for its further object a

simple mechanism controlled by pressure variations and controlling the lighting and extinguishing of a gas-jet or any number of such.

In order that my invention may be fully understood, I will describe the same in detail, reference being had to the accompanying drawings, in which—

Figure 1 is a vertical sectional view illustrating one form of appliances for producing momentarily pressure variations in a gas-supply pipe and one form of appliances operated by said variations and operating to light or extinguish a burner-jet, and Figs. 2 and 3 are vertical sectional views illustrating modified constructions of the appliances controlled by pressure variations.

The appliances controlled by pressure variations consist, essentially, as follows: of a casing a' , provided at one end with an internally-threaded passage a'' for connection thereto of a gas-supply pipe P and at the opposite end with an externally-threaded branch or boss w for connection thereto of a burner or burner-pipe; of a main gas-passage leading to the branch w ; of a by-pass l' , having a small, preferably conical, port r , controlled by a cone screw-valve s and communicating with the casing a' and with an igniter-burner pipe u , as shown in Fig. 1, or with the main supply-passage, as shown in Figs. 2 and 3; of a cut-off valve which may control the supply of gas to the main and igniter burners, as shown in Fig. 1, or said valve may control the supply of gas to the main burner only, as shown in Figs. 2 and 3; of a diaphragm i , arranged in one side of the casing, and of a valve-operating mechanism controlled by said diaphragm.

The appliances for producing momentary pressure variations consist, broadly speaking, of a receiver connected to the gas-supply pipe P and means for driving out the gas therein to increase the pressure in the supply-pipe and casing a' and of means for drawing gas from the supply-pipe by suction into said receiver for the purpose of reducing the pressure in the supply-pipe and in said casing, whereby the diaphragm is deflected in one or the other direction and the valve operated to

open or close the main supply-passage to the burner or burner distributing-pipes or to the latter and the igniter-burner.

Referring more particularly to Fig. 1, the 5 casing a' has two oppositely-arranged passages t and t' , whose outer faces are reversely inclined and form valve-seats for a flap-valve p , secured to a rocking spindle o , provided with two radial arms n , one of which is always 10 in engagement with a toothed rack m at the upper end of a rock-lever l , fulcrumed at l' . This lever is connected above its fulcrum to a lever k through a link l'' , and said lever k is fulcrumed at k' and has its shorter arm pivoted to a suitable bracket secured to the diaphragm. The passage or by-pass t' communicates with a chamber c' through a small 15 conical port r , controlled by a cone screw-valve s , and to said chamber is connected the 20 pilot or igniter burner pipe u .

In Fig. 1 I have shown a receiver b , made of a flexible impermeable material and containing a distending or expanding spring b' for producing pressure variations in pipe P 25 and casing a' , said receiver being connected by a pipe P' to said pipe P . The receiver b is contained in a casing a , in which is guided a follower or push-button c , having formed therein a notch or recess f , adapted to be engaged by a locking-pin e on a rod d , provided with a knob or button d' . The rod d is pivoted at d'' in a hanger g , pivoted at g' to a bracket in the casing a , and is held in a normal nearly horizontal position by a coiled 30 spring h , secured to the casing and into which the rear end of the rod projects, so that when the push-button is pushed into the casing to its full extent the radial pin e will snap into the notch f and lock the button c against outward movement under the stress of the 35 spring b' .

The operation of the apparatus is as follows, it being assumed that the receiver b' has been suddenly expanded to produce a suction impulse in casing a' , whereby valve p has been shifted from its seat on t to its seat on t' to supply gas to the main burner and cut off the supply of gas to the igniter or pilot burner tube u , one of the radial arms n on rocking 40 spindle o lying on the left of the center tooth of the rack at the upper end of the shifting lever l and the companion radial arm on said spindle lying on the right and above said tooth: To cut off the supply of gas to the main-burner 45 passage w and to supply gas to the pilot-burner tube u , the receiver b is suddenly compressed against the stress of its expanding spring, the sudden increase of pressure in casing a' deflecting diaphragm i outwardly and 50 moving lever l to the left, the center tooth acting on radial arm n on its right and shifting valve p from its seat on t' to its seat on t , thereby also moving the companion radial arm n on spindle o to the left side of said center 55 tooth, so that when a sudden suction or par-

tial vacuum is produced in casing a' by the sudden expansion of receiver b , the diaphragm i being then deflected inwardly and lever l shifted to the right, its center tooth act on the said radial arm n on its right and shift the valve from its seat on t to its seat on t' —i. e., back to its position shown in Fig. 1. These operations may, however, be reversed by simply reversing the position of valve p on its spindle o so that a reduced pressure or 75 suction in a' will shift the valve from t' to t and a sudden increase of pressure from t to t' . This may also be effected by reversing the location of the passages t' and t , Fig. 1, as will be readily understood. Inasmuch as the by-pass t' is opened or closed a little before the 80 passage t is closed or opened, gas admitted to the igniter-burner in the first case will be ignited by the main-burner flame before the latter is extinguished and in the second case the 85 gas admitted to the main-burner flame will be ignited by the flame of the igniter-burner before the latter is extinguished.

The valve apparatus shown in Fig. 2 is in all respects like that shown in Fig. 1, except that 90 the main gas-supply passage t is extended downward below its inlet to form a by-pass t' , which, as above stated, is in communication with the casing through port r , controlled by hand-valves, and in that the throw of the valve p to the left is limited by an abutment g .

In Fig. 3 I have shown a modification of the valve-controlling mechanism. In this modification I provide a gravity-valve p^4 , controlling a main passage or port leading to branch w and axially thereof, said valve resting when on its seat on the end of a lifting-lever p^2 , controlled by a wheel p' , having teeth p^3 , that act on lever l^4 and lift it, and therethrough the valve p^4 , to open the main supply-passage. 105 On the spindle of wheel p' is secured a ratchet-wheel n' , actuated by a pawl m' , pivoted to lever l^4 , that is rocked by the diaphragm i , as in the case of lever l .

There is a further difference in the construction of the cut-off valves shown in Figs. 2 and 3 from that shown in Fig. 1 in that the igniter-tube u is dispensed with and a small amount of gas constantly supplied to the main burner through the by-pass t' to keep it 110 lighted when the main supply-passage is cut off by the valve p , Fig. 2, or the valve p^4 , Fig. 3. The operation of this apparatus is substantially as above described, and the pressure variations for vibrating the diaphragm 115 may be produced by the appliances above referred to or they may be produced by temporary or momentary pressure variations in the distributing system.

This apparatus has the advantage of providing means whereby all or any number of jets may be lighted and extinguished at different periods by suitably varying the number and relative position of the teeth on the valve-actuating wheels p' , which control the 120 125 130

supply of gas to the individual burners. Thus, for instance, if it is desired to light and extinguish certain lamps at certain locations at stated periods and other lamps at other points at another stated period the teeth on the controlling-wheels p' , which control one set of valves, may be arranged so as to open or close the valve p^t at each pressure variation, while the teeth on the wheels that control the other set of valves may be arranged to open and close the same by varying the pressure successively a greater or less number of times. It is obvious, however, that in either case the pressure variations are momentary only, so that if the invention is applied to the lighting and extinguishing of street-lamps supplied through a network of piping common to all the lights in a city or district the variations in the pressure would affect the house-lights but momentarily and only at such times when the street-lamps are extinguished, while at all other times the pressure in the network may remain normal. It is furthermore obvious that the pressure-varying apparatus may be used for controlling a single burner or any number of burners in a building, or it may be installed at the gas-works or at the different supply-stations. It will furthermore be understood that any other suction and forcing device may be used instead of the flexible, expandible, and collapsible receiver b , such as a bellows-shaped receiver or a cylinder and piston or the like.

Having thus described my invention, what I claim as new therein, and desire to secure by Letters Patent, is—

1. In combination, a gas-supply pipe, a burner-passage in communication therewith, a cut-off valve adapted to be operated by gas impulses produced by variations of the pressure in the supply-pipe to open and close said passage, a branch pipe connected to said gas-supply pipe and means connected to said branch pipe and adapted to be operated by hand to produce the aforesaid pressure variations in the supply-pipe, substantially as and for the purposes set forth.

2. The combination with a gas-conduit, a burner-passage in communication therewith and a valve adapted to be operated by gas impulses produced by a sudden increase or a sudden decrease of the pressure in the conduit; of a collapsible receiver in communication with said gas-conduit and means automatically and rapidly expanding said receiver when collapsed, for the purpose set forth.

3. A gas-conduit, a burner-passage leading therefrom, a valve adapted to be moved by variations of the pressure in the conduit to open or close said passage, and a suction and forcing device comprising a receiver connected to the conduit and made of a flexible material, means for compressing the receiver, means adapted to lock the latter against expansion and to again release it and means for

expanding said receiver independently of the gas-pressure, for the purpose set forth.

4. A gas-conduit, a burner-passage leading therefrom, a valve adapted to be moved by variations of the pressure in the conduit to open or close said passage, and a suction and forcing device comprising a receiver connected to the conduit and made of a flexible material, a spring contained therein and tending to expand the same, means for compressing the receiver and means adapted to lock the same against expansion, for the purpose set forth.

5. A gas-conduit, a burner-passage leading therefrom, a valve adapted to be moved by variations of the pressure in the conduit to open or close said passage, and a suction and forcing device comprising a receiver connected to the conduit and made of a flexible material, a spring contained therein and tending to expand the same, a follower adapted to compress said receiver, provided with a lock-notch, a pivoted rod carrying a radial arm adapted to engage said notch when the receiver is compressed, and a coiled spring acting on the free end of the rod to hold it in a normal position, for the purpose set forth.

6. The combination with a gas-conduit, a burner-passage in communication therewith, a cut-off valve controlling said passage, a toothed wheel and mechanism adapted to be operated by gas impulses produced by variations of the pressure in the conduit to impart to said toothed wheel a step-by-step rotation; of a valve-actuating device operated by said toothed wheel to move the valve from or to its seat, for the purpose set forth.

7. The combination with a gas-conduit, a burner-passage in communication therewith, a cut-off valve controlling said passage, a toothed wheel and mechanism adapted to be operated by gas impulses produced by variations of the pressure in the conduit to impart to said toothed wheel a step-by-step rotation; and a valve-actuating device operated by said toothed wheel to move the valve from or to its seat; of a hand-operated device for producing the aforementioned impulses, substantially as set forth.

8. The combination with a casing provided with two gas-passages, with a diaphragm in one of its sides and with means for connecting it to a gas-supply pipe, a gravity-valve controlling the flow of gas to one of said passages and a lifting-lever in perpetual contact with said valve; of a toothed wheel and a ratchet-wheel revoluble in unison, said toothed wheel in perpetual contact with the lifting-lever, a pawl-lever actuating the ratchet-wheel and means connecting the pawl-lever to the diaphragm and adapted to rock said lever and thereby impart a progressive rotation to the ratchet-wheel when the diaphragm is vibrated by pressure variations in the casing, for the purposes set forth.

9. The combination with a casing provided with two gas-passages, with a diaphragm in one of its sides and with means for connecting it to a gas-supply pipe, a gravity-valve 5 controlling the flow of gas to one of said passages and a lifting-lever in perpetual contact with said valve; of a toothed wheel and a ratchet-wheel revolvable in unison, said toothed wheel in perpetual contact with the lifting- 10 lever, a pawl-lever actuating the ratchet-wheel and means connecting the pawl-lever to the diaphragm and adapted to rock said lever and thereby impart a progressive rotation to

the ratchet-wheel when the diaphragm is vibrated by pressure variations in the casing 15 and a suction and forcing device connectible to the casing for varying the pressure therein, for the purposes set forth.

In testimony that I claim the foregoing as my invention I have signed my name in presence of two subscribing witnesses.

FRITZ ROSSBACH-ROUSSET.
